(No Model.)

J. S. COLE.

COMBINED CLOTHES RACK, IRONING TABLE, AND CLOTHES DRIER.

No. 427,051.

Patented May 6, 1890.

UNITED STATES PATENT OFFICE.

JOSEPH S. COLE, OF ALBANY, INDIANA, ASSIGNOR OF ONE-HALF TO LEWIS H. BALDWIN, OF SAME PLACE.

COMBINED CLOTHES-RACK, IRONING-TABLE, AND CLOTHES-DRIER.

SPECIFICATION forming part of Letters Patent No. 427,051, dated May 6, 1890.

Application filed November 9, 1889. Serial No. 329,821. (No model.)

To all whom it may concern:

Be it known that I, JOSEPH S. COLE, a citizen of the United States, residing at Albany, in the county of Delaware and State of Indiana, have invented a new and useful Combined Clothes - Rack, Ironing - Table, and Clothes-Drier, of which the following is a specification.

This invention has relation to a combined clothes-rack, ironing-table, and clothes-drier; and the invention consists in certain novel features of construction, hereinafter specified, and particularly pointed out in the claims.

Referring to the drawings, Figure 1 is a perspective of a combined clothes rack, drier, and ironing-table constructed in accordance with my invention, the same being arranged in position for ironing. Fig. 2 is a similar view, the board removed and the frame arranged as for drying clothes. Fig. 3 is a detail of the construction of the joint between the side bars of the swinging top frame, the intermediate drop-frame, and the rearwardly-disposed legs. Fig. 4 is a detail of one end of the ironing-board.

Like numerals of reference indicate like parts in all the figures.

1 represent two opposite parallel inclined vertically-disposed legs, which are connected at their upper and lower ends by cross-bars 2 and 3.

5 represents a series of cross-bars—in this instance two—connecting the legs 1. The upper cross-bar 2 has reduced ends 6 entering openings 7 in the upper ends of the legs 1.

8 represents a pair of vertically-disposed inclined supporting-legs, having at their middle outwardly-extending studs 9, adapted to take into circular openings 10, formed in the bars 1, whereby the legs 1 and 8 are pivotally connected. A cross-bar 11 and a second cross-bar 12 connect the lower and upper ends of the legs 8.

13 represents opposite horizontal side bars, the rear ends of which are connected by hinges 14 to the front edge of the legs 1, and the under surfaces or lower edges of the side bars 13 are provided with a series of inwardly-disposed inclined recesses 15, adapted to take over the cross-bar 12, connecting the upper

ends of the legs 8, and thus adjust the bars 13 to different heights.

16 represents an ironing-board, provided on its under surface and near one end with detachable leaves 17 of hinges. The opposite leaves 18 are secured to the inner faces of one of the bars 13, so that the board may be detachably mounted within the bars and removed when not in use. The board is covered with a suitable padding, and the upper end of the same is reduced to form a bosom-board 19.

Upon the upper tie-bar 2 of the series connecting the legs 1, and upon the reduced opposite ends thereof, are loosely mounted a pair of parallel bars 20, the ends of which are connected by a cross-bar 21, the bars 20 and 21 forming an intermediate drop-frame. Upon the bars 21 is pivotally connected a shorter pair of bars 22, which depend from the cross-bar 21, and are connected at their lower ends by a cross-bar 23, the ends of which are pivoted in openings formed in the side bars 13 near their rear ends, thus forming a lower extension-frame.

Upon the upper bar 2 of the series connecting the legs 1 there is loosely pivoted within the bars 20 a second pair of parallel bars 24, of greater length than the bars 20, and connected at their middle by a cross-bar 25 and at their ends by a cross-bar 26, the extremities of which pass through the bars 24 and into openings 27, formed in the upper ends of a pair of bars 28, connected at their lower ends by a cross-bar 29. The side bars 24, connected as described, form a swinging top frame, while the shorter bars 28 and their cross-bars constitute a top detent extension-frame. The bars 28 terminate at their lower ends in studs or tenons 30, which are adapted to take into either one of a series of pairs of perforations 31, formed in the upper surface of the side bars 13, or in a pair of perforations 32, formed in the lower ends of the side bars 20, as shown by dotted lines in Fig. 2.

I have for the purposes of clearer description termed the parts comprehended by the numerals 24 and 25 the "swinging top frame," and parts 28 and 29 the "top detent extension-frame;" the parts 20 and 21 the "inter-

mediate drop-frame;" the part 22, with its connecting - bar 23, the "lower extension-frame;" the parts 1 and 8 the "crossed legs," and the side bars 13 the "board-supporting frame." By this means the confusion of terms by calling all the parts "bars" may be avoided.

When the ironing-board is in position and the frame acts as a support for the ironing-board, the swinging top frame and its detent extension are swung upward out of the way, as shown in Fig. 1, and, in connection with the remainder of the frame formed by the crossed legs and intermediate drop-frame and its extension and their connecting-bars, serve as a rack for supporting articles during ironing. When, however, the ironing-board is removed, the swinging top frame and its detent extension are swung down, and the ten-

20 ons 30 either enter into the perforations 31 or 32, as may be desirable and convenient, and thus the rack serves as a clothes-drier.

Having thus described my invention, what I claim, and desire to secure by Letters Patent,

25 is—

1. The combination, with inclined side bars 8 and the longer side bars 1, the former connected at their upper ends by the cross-bar 12 and the latter by a series of bars 5 and 30 an upper bar 2, of the table-supporting bars 13, pivoted to the bars 1 and adjustably connected to the connecting-bar 12, the intermediate drop-frame, the side bars 20 of which are pivoted at their upper ends to the bar 2, 35 and the lower extension-frame, the side bars

22 of which are pivoted at their upper ends to the lower ends of the bars 20 and at their lower ends to the table-supporting bars 13, substantially as specified.

2. The combination, with inclined side bars 40 8 and the longer side bars 1, the former connected at their upper ends by the cross-bars 12 and the latter by a series of bars 5 and an upper bar 2, of the table-supporting bars 13, pivoted to the bars 1 and adjustably connected to the connecting-bar 12, the intermediate drop-frame, the side bars 20 of which are pivoted at their upper ends to the bar 2, the lower extension-frame, the side bars 22 of which are pivoted at their upper ends 45 to the lower ends of the bars 20 and at their lower ends to the table-supporting bars, the top swinging frame, the bars 24 of which are pivoted at their lower ends to the bar 2, and the top detent extension-frame, the side bars 55 28 of which are at one end pivoted to the free ends of the swinging top frame and the opposite ends of which are provided with tenons adapted to enter openings 31, formed in the table-supporting bars 13, or similar openings 32, formed in the side bars 20, substantially as specified.

In testimony that I claim the foregoing as my own I have hereto affixed my signature in presence of two witnesses.

JOSEPH S. COLE.
